UNITED STATES PATENT OFFICE.

HENRY H. HYLAND, OF PITTSBURG, PENNSYLVANIA, ASSIGNOR OF ONE-HALF TO THOMAS H. PHELPS, OF SAME PLACE.

STEAM-GENERATOR.

SPECIFICATION forming part of Letters Patent No. 394,574, dated December 18, 1888.

Application filed April 5, 1888. Serial No. 269,678. (No model.)

To all whom it may concern:

Be it known that I, HENRY H. HYLAND, a citizen of the United States, residing at Pittsburgh, in the county of Allegheny and State of Pennsylvania, have invented certain new and useful Improvements in Steam-Generators; and I do hereby declare the following to be a full, clear, and exact description of the invention, such as will enable others skilled in the art to which it appertains to make and use the same.

My invention relates generally to devices for generating steam, and particularly to that class of generators in which petroleum and other hydrocarbon oils are used as fuel.

The object of my invention is to construct a device that will generate steam rapidly and economically. To accomplish these objects, I first so construct the furnace that a perfect circulation of the water is secured, and, second, so arrange the air-supply that the air will commingle with the flame at the best point to produce perfect combustion.

The nature of the invention will more fully appear from the subjoined description and the accompanying drawings, and the novelty be pointed out in the claim.

Referring to the drawings, Figure 1 represents an elevation of my improved construction; Fig. 2, a transverse section; and Fig. 3, a horizontal section on line W W, Fig. 2.

A represents the outer shell of the furnace, which is imperforate from top to bottom, except at the points hereinafter described. It is surmounted by a dome, A', of any suitable construction, and provided with a collar, a', for the stack. To the upper and lower ends of the shell are secured, respectively, sheets A² and A³. Sheet A² has an annular flange 40 by which it is secured to the shell A, and sheet A³ is preferably secured by means of an annular ring, A⁴, which is bolted to both the shell A and sheet A³, as shown. Within the shell A is a second shell, A⁵, having heads or 45 sheets A⁶ and A⁷, arranged, respectively, at the upper and lower ends and secured thereto by bolts passing through the flanges of the same. The upper head, A⁶, is secured to the sheet or head A³ by tubes A⁸ for the escape 50 of the products of combustion from the inner

shell, A⁵. In this shell is placed a drum, A⁹, having radial pipes A¹⁰, which connect the drum with the water-space D between the shells A and A⁵, and the water-tubes A¹² and A¹³, which respectively connect the drum with the water-spaces D' and D² between sheets A³ A⁶ and A³ A⁷. From the head projects a water-ring, A¹⁴, to support the steam-dome A¹⁵, which is provided with a steam-escape pipe, A¹⁶, and inclosed by a perforated cylinder, A¹⁷, 60 which protects it from the flame passing out of the tubes A⁸. This cylinder is held in place by an annular collar, a, on the upper side of head A². All of these parts are inclosed by the dome A'. If desired, a water-gage, A¹⁸, 65 may be connected with the drum and water-space between the shells.

B is the combustion-chamber, formed by the inner shell and its heads. The drum A⁹ is located near the middle or center of the same 70 and divides it into two parts, the lower part being the fire-box proper and the upper part, B', a secondary combustion-chamber. The lower part, B, is provided with an opening, b, which is formed by a pipe that passes through 75 the outer and inner shells and the water-space D, and air-tubes b', which are formed in the same manner as the opening b and are upon the same horizontal plane. The opening b receives the oil or gas supplier b², which furnishes the fuel for the generator. By this construction the air is made to commingle with the flame at the point of combustion of the gas, so that the air, instead of cooling the gases and retarding combustion, materially 80 assists in furnishing a proper combustion. Another result is the perfect circulation of the water, which is accomplished by connecting the water-space D² with the drum by means of pipes A¹³ in the combustion-chamber, where 85 said pipes are thoroughly heated, as well as pipes A¹⁰ and A¹² and the drum A⁹. The pipe A¹³ draws the water from the space D² into the drum, where it is distributed by pipes A¹⁰ and A¹² to water-spaces D' and D. The hot- 90 test water passes through pipes A¹⁰ into the water-space D', and the cooler water is passed by the radial pipes into the water-space D and returns to the bottom space, D², from which it is drawn by the pipes A¹³. The feed-water 95 100

pipe C may be arranged at any point in the system, but the place shown is the one preferred.

While I show the fire-box of this generator adapted to use vapor fuel, I do not wish to limit myself to that kind of fuel, as it is obvious that very slight changes in the fire-box can be made to adapt it for solid fuel. In other words, I do not limit my construction to a gas-burning device, but purpose to use any kind of fuel, and only show the gas-burning device as one form of fire-box.

What I claim as new is—

In a steam-generator, the combination of a

fire-box entirely inclosed by a water-chamber 15 and having a fuel-opening through the water-space, and radial air-supply tubes arranged substantially as shown, and a water-drum in said fire-box and connected with the top, bottom, and lateral water-spaces around said fire-box.

In testimony whereof I affix my signature in presence of two witnesses.

H. H. HYLAND.
